E. V. MENDELL.
TABLE MAT.
APPLICATION FILED DEC. 23, 1913.

1,214,054.

Patented Jan. 30, 1917.

UNITED STATES PATENT OFFICE.

ELBERT V. MENDENHALL, OF LOS ANGELES, CALIFORNIA.

TABLE-MAT.

1,214,054.

Specification of Letters Patent. Patented Jan. 20, 1917.

Application filed December 22, 1912. Serial No. 303,391.

To all whom it may concern:

Be it known that I, ELBERT V. MENDENHALL, a citizen of the United States, residing at Los Angeles, in the county of Los Angeles and State of California, have invented a new and useful Table-Mat, of which the following is a specification:

This invention relates to mats adapted to be placed on top of a table, to protect the surface of the table from injury by hot or heavy articles placed thereon, and the main object of the invention is to provide a mat which can be folded into small compass or can be opened out in such manner as to present a substantially continuous flat surface.

Another object of the invention is to provide a folding mat which can be folded equally well in either direction.

20 A further object of the invention is to provide a table mat of simple and cheap construction and of great efficiency as a thermal insulator.

Other objects of the invention will appear hereinafter.

The accompanying drawings illustrate an embodiment of my invention, and referring thereto:

Figure 1 is a plan view of the complete mat in flat or extended position on a circular table. Fig. 2 is a side elevation of the table with the mat thereon. Fig. 3 is a section on line x^3-x^4 , in Fig. 1. Fig. 4 is an end view of the mat in folded position, with the covering fabric removed at the ends. Fig. 5 is a section on line x^5-x^6 in Fig. 6. Fig. 6 is a section on line x^6-x^7 in Fig. 5. Fig. 7 is an end elevation of the mat in extended or flat position, partly broken away. Fig. 8 is a transverse section of the hinge joint on line x^8-x^9 in Fig. 9. Fig. 9 is a plan view of a joint portion of the mat. Fig. 10 is a perspective and Fig. 11 an end view of such joint portion, the joint being bent partially open in Fig. 10. Fig. 12 is a vertical section of a modified construction of the mat. Fig. 13 is a vertical section of a modified form of the reversible joint.

The mat as constructed for use on a circular table, comprises three members, namely: a central member 1 and two wings 2, hinged to the central member at 3, to form when extended, a semi-circular mat,

so that when two of such mats are placed with their straight faces in opposition, as shown in Fig. 1, they will form a circular mat for covering a round table, indicated at 4 in Fig. 2. Each of the members 1 and 2 is of similar construction and comprises upper and lower sheets or boards 5 and 6 with an intervening member 7 acting as a cushion and thermal insulating means. The said member 7 may consist of corrugated paper board cemented to the top and bottom sheets 5 and 6, and said top and bottom sheets may consist of paste-board, preferably of a porous, soft nature, for example, the material known to the trade as building felt. In place of the corrugated paper core member 7 any other suitable insulating means may be used, for example, cork or cork composition, or other compositions or materials containing a large quantity of air, and, therefore, of a cushioning and thermal insulating property, Fig. 12 illustrating the construction when such a composition indicated at 7 is used.

The member 1 is connected to each of the members 2 by a hinge, permitting folding of said members on one another in either direction. Said hinge comprises a hinge-strip 8 extending between the members 1 and 2, said strip being of any suitable material, for example, wood, and hinge-flaps 9 secured to the members 1 and 2 and to said strip. One flap 9 extends on top of one of the members 2 near the hinged edge thereof, and then in the form of a loop 10 down inside of the hinged edge and then up over the hinge-strip 8 and over adjacent portions of the central member 1, this hinge-flap or sheet being glued or cemented to the members 1, 8 and 2, where it lies in contact therewith. The other hinge-flap or sheet 9 extends beneath the aforesaid member 2 and beneath the hinge-strip 8, and then up and down in the form of a loop 10 between said hinge-strip 8 and the member 1, and then underneath the member 1, said hinge-flap or sheet 9 being secured by glue or otherwise to the bottom faces of the members 1, 8 and 2, and to the opposing edge faces of members 1 and 8 at the loop portion 10. The hinge flaps or sheets 9 above described may be of any suitable flexible material, for example, a strong fabric or cloth and

may extend the full length of the hinge-joint between the members 1 and 2 or only a portion or portions of such length.

- In order to draw the several members of 5 the mat closely together to make a substantially continuous surface, I provide spring means 12 consisting, for example, of a helical spring located within a channel 13 formed at each end of the member 1, and 10 being connected by cords 14 at its ends to the respective members 2. The grooves 13 may be formed in the member 1 by removing or omitting from the edge portions thereof the central sheet or core member 15 7, and similar channels may be formed in the members 2 for receiving the tension cords 14 aforesaid. Straps 15 are provided over these grooves for retaining the cords when the mat members are bent at the joint. 20 Said cords may be secured to the spring and to the members 2 in any suitable manner, for example, they may be looped through the spring near the ends thereof, and fastened to the members 2 by clips 11. 25 A suitable protective and cushioning covering 16 of cotton felt or other soft material is preferably provided as a facing for the edges and bottom of the mat, said material being pasted or otherwise secured to the 30 members 1 and 2, and to the lower hinge-flaps 9, so as to fold at the hinges within said hinge flaps. The top of the mat is covered with a waterproof sheet 17 of oil-cloth or other suitable material pasted to 35 the top of the members 1 and 2 and to the upper hinge flaps 9, and extending down between the said members and the intermediate hinge-strips 8, in a loop to form a hinge upon which said members swing. 40 The sheet 17 forms a continuous uncut waterproof surface over the entire semicircular mat and provides a waterproof hinge which enables the members to fold in either direction, this sheet folding within the upper 45 hinges. These upper and lower cover sheets also serve as hinges, the hinge-flaps 9 simply reinforcing the hinge action of these sheets. This waterproof top 17 preferably extends beyond the inner or straight 50 edge of the members 1 and 2 as shown at 18 in Figs. 1 and 2, so as to overlap the adjacent edge portion of the other half of the circular mat, and this overlapping flap 18 is cut as at 18' to enable the flap to be 55 folded flat, when the mat is extended as shown in Fig. 11, and to enable said flap to lie flat on said other half of the circular mat.
- When the mat is placed on the table the 60 several members thereof occupy the positions shown in Figs. 3 and 7, all of the members 1, 2 and 8 lying flat on the table with the hinge-loops 10 at one side of the members 8 extending downwardly from the 65 top and the hinge-loops at the other side

of the members 8 extending upwardly from the bottom, the tension springs 12 serving to draw the end members 2 toward the central member 1, so as to hold said members flat and prevent them from buckling up by the elasticity of the material of the hinges. When it is desired to fold the mat, the end members 2 may be folded respectively on top of and beneath the central member 1, the hinge joint above described permitting either of the end members 2 to be folded on top and the other of said members 2 to be folded beneath the member 1, so that the person folding the mat can not damage the same by inadvertently folding it in the wrong direction. The intermediate hinge strip 8 may be provided with keepers or staples 8' embracing the spring cord 14 to hold it from slipping off the strip when the hinge is bent.

It will be understood that the mat may have any desired number of sections or members and that the shape of these members may be varied according to the shape of the surface it is desired to cover.

As shown in Fig. 13, the intermediate wooden strip 8 may be omitted, the portion or strip 20 of the hinge and cover fabrics between the mat members 21 and 22 being connected at the upper edge thereof to the member 21 and at the lower edge thereof to the member 22, so that in folding the member 22 over the member 21, said members hinge on the junction of the upper edge of this hinge strip 20 with member 21 and in folding them in the reverse direction they hinge on the junction of said strip with the lower mat member.

What I claim is:

In combination, central and wing members each formed of upper and lower sheets, a hinge-strip extending between said central and wing members, hinge-flaps secured to the central and wing members, one hinge-flap extending on top of the wing member near the hinged edge thereof and extending in a loop down between the hinge-strip and wing member and extending over the hinge-strip and over adjacent portions of the central member, said hinge-flap being fastened to the top faces of the central and wing members and to the top face of the hinge-strip, the other hinge-flap extending beneath the wing member and beneath the hinge-strip and extending in a loop between the hinge-strip and central member and extending underneath the central member, and said other hinge-flap being fastened to the bottom faces of the central and wing members and to the bottom face of the hinge-strip, and a continuous waterproof sheet covering the central and wing members and extending in a loop down within the loop of one of said hinge-flaps, said water-proof sheet extending beyond

the inner adjacent edges of the central and wing members so as to overlap the adjacent edge portion of other similarly constructed central and wing mat members and the overlapping flap being cut to enable it to be folded flat when the mat is extended and to enable said flap to lie flat on said other similarly constructed mat members.

In testimony whereof, I have hereunto set my hand at Los Angeles, California this 10
15th day of December, 1913.

ELBERT V. MENDENHALL.

In presence of—
ARTHUR P. KNIGHT,
LORRAINE E. DURROW.
